PHOTO EQUIPMENT CARRYING CASE

Paul F. Bates, Sr., 139 Sackett Road,
Westfield, Mass. 01085

Filed Oct. 9, 1974, Ser. No. 513,255

Term of patent 14 years

Int. Cl. D3—02

U.S. Cl. D87—5 E

FIG. 1 is a top front perspective view of a photo equipment carrying case showing my new design;
FIG. 2 is a rear elevational view thereof;
FIG. 3 is a left side elevational view thereof; and
FIG. 4 is a bottom plan view thereof.

I claim:

The ornamental design for a photo equipment carrying case, as shown and described.
